Primary Examiner—Carol Rademaker*(74) Attorney, Agent, or Firm*—Connolly Bove Lodge & Hutz LLP(57) **CLAIM**

The ornamental design for a bottle, as shown and described.

DESCRIPTION

FIG. 1 is a top left front perspective view of a bottle showing the invention;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The broken lines shown in the drawings are included for the purpose of showing environmental structure that forms no part of the claimed design.
